UNITED STATES PATENT OFFICE.

NICHOLAS A. WIERMAN, OF TROY, OHIO.

EGG-PRESERVING CASE.

SPECIFICATION forming part of Letters Patent No. 781,479, dated January 31, 1905.

Application filed July 2, 1904. Serial No. 215,127.

To all whom it may concern:

Be it known that I, NICHOLAS A. WIERMAN, a citizen of the United States, residing at Troy, in the county of Miami and State of Ohio, have invented a new and useful Improvement 5 in Egg-Preserving Cases, of which the following is a specification.

My invention is in the nature of a novel egg-preserving case. It is an improvement 10 in the class of egg-preserving cases in which the eggs are held in cells in a case suspended on trunnions or journals, whereby the case can be turned from time to time to prevent the yolk from settling to one side of the shell, 15 in which position it soon spoils.

My invention consists in the novel construction and arrangement of the cases in series one above the other in an upright frame with means for removing the cases from the 20 frame and inserting them again and for giving access to the cases and for fixing the positions of the cases in the frame.

It also consists in the construction and arrangement of the cell-partitions for holding 25 and spacing the eggs in such manner as to permit them to be compactly stored, firmly held, and thoroughly ventilated and to permit them to be turned over without shock or jar, as will be hereinafter fully described with reference 30 to the drawings, in which—

Figure 1 is an end view, partly in section, on line 1 1 of Fig. 2. Fig. 2 is a side view. Figs. 3 and 4 are details of the cell-forming partitions, and Fig. 5 is a detail of the locking-bar.

In the drawings, A represents a suitable 35 base upon which are erected two vertically-parallel standards B B, connected at the top by a cross-bar C. In the adjacent faces of these standards are formed vertical grooves 40 with bearing blocks or stops a at suitable intervals which form bearings for the trunnions b b of the rotary adjustable cases D D D. These trunnions are mounted on cross-bars at the ends of the cases, which cases are otherwise 45 open at the ends for purposes of ventilation. There may be any number of these cases arranged in vertical series one above the other, each having its trunnions resting in the grooves of the standards upon the bearings a. 50 Each case is composed of four equal and

square sides with open ends, one side D' of each case being made removable and being detachably secured by means of a spring locking-bar d, pivoted in the middle and having keyhole-slots d' at the end which are adapted 55 to receive the heads of screws or headed pins d² d², whose heads pass through the large ends of the keyhole-slots d'. When the heads pass through and the bar d is turned about its pivot, the edges of the narrow ends of the 60 slots pass under the heads of the screws, and thus lock the removable side of the case in place to close the same. The removability of this side of the case permits the cell-partitions and the eggs to be put into or taken out of 65 the case. By the mounting of the cases on horizontal trunnions the cases, with the eggs, may be turned partially over, and the position of the eggs are thus changed as often as may be desired. To fix the various positions of 70 the cases, pins or set-screws E are tapped through one of the standards and are made to enter seats e in the ends of the case, and thus hold the latter to any of its four positions to which it may be turned. To put 75 the cases into or take them out of the frame, lateral outlet-slots c c are formed in the standards, which lead into the grooves in the adjacent faces of the standards. These outlets are located a distance above the bearing-blocks a 80 less than the difference between a radial line passing through the angle of the case and a radial line passing through the side of the case midway between the angles. The bearing-blocks a are also spaced vertically in the 85 grooves of the standards, so that the cases may revolve freely without touching each other at their outer angles. If, however, any case is turned so that two of its sides are horizontal, then the case may be lifted high enough 90 (see dotted lines in Fig. 1) so that its trunnions can rise to the outlets c before such case strikes the next one immediately above it. This permits the cases to be arranged in vertical series quite close together and yet permits the cases to be independently rotated and also independently raised and lifted out of the frame without disturbing the others. 95

For packing the eggs within the cases I have devised a special cell-partition F, (shown in 100

Figs. 3 and 4,) which is designed with reference to preventing the eggs from being jolted or individually shifted while being turned and also with reference to securing the most compact storage of the eggs and a free ventilation or passage of air through the same. These cell-partitions are simply sheets of woven wire crimped or bent into zigzag angles and having these angles connected by stay-bars $f f$ 5 at the ends, which bars or braces by uniting the apices of the angles prevent the spreading out of the partitions, and thus keep them within the limits of the sides of the case. The parallel channels of each partition are in depth 10 equal to about one-half the thickness of an egg, so that it takes two partitions to form a complete set of egg-channels. When the cell-partitions are put in the case in the relation shown in Fig. 4, the angle of one partition co-operates with the angle of the next adjacent partition, so as to form complete parallel chambers in which the eggs are packed, and when the eggs are so placed each egg is held at four points by the tangential contact 15 of the sides of the two cell-partitions with a somewhat elastic grip that prevents breakage from individual movement of the egg and causes all of the eggs to be held alike and to be turned alike when the cases are rotated on their trunnions. There is therefore a special 20 correlation between the form of cell-partition and the rotary character of the case which prevents all shock and jar and individual movement of the eggs. As the cases are open at 25 the ends, it will be seen that the partition-braces $f f$ not only act to prevent the spreading of the crimped partitions, and thus prevent the crushing of eggs from the superincumbent weight of the eggs above, but it will be seen 30 that these braces extend directly across the middle line of the rows of eggs and keep them from dropping out the ends of the channels, which is an important result when the ends of the cases are left open for ventilation, as 35 shown.

If desired, the case may be made with only one of the receptacles D, or it may, as before stated, have any number of the same arranged in vertical series, which secures great economy 40 of floor-space and easy inspection and access.

Having thus described my invention, what I claim as new, and desire to secure by Letters Patent, is—

1. An egg-preserving case consisting of a

vertical series of receptacles having square sides, one of which sides is made removable, and having open ends with cross-bars provided with trunnions; combined with a supporting-frame composed of a base and two vertical and parallel standards having vertical, longitudinal grooves in their adjacent faces with bearings in the grooves for the trunnions and lateral outlets for the grooves above the bearings to permit the receptacles to be independently removed substantially as and for the purpose 65 described.

2. An egg-preserving case consisting of a vertical series of receptacles having square sides, and trunnions at the ends, combined with a supporting-frame composed of a base and 70 two vertical and parallel standards having vertical, longitudinal grooves in their adjacent faces, with bearings in the grooves for the trunnions and lateral outlets for the grooves located above the bearings a distance less than 75 the difference between the radial line passing through the angle of the case and a radial line passing through the side of the case midway between the angles, substantially as and for the purpose described.

3. An egg-case mounted on a horizontal axis to rotate and provided with cell-partitions formed of woven wire arranged in zigzag form forming channels of half the thickness of an egg and having their apices connected by stay-braces to prevent the crimps from spreading and for holding the eggs against moving endwise out of the channels substantially as described.

4. A cell - partition made of angularly-crimped woven wire, the crimps forming parallel channels of half the thickness of an egg and maintained in zigzag form by stay-braces at the ends and two of said partitions forming one complete set of egg-channels substantially 85 as described.

5. An egg-case having four square sides with open ends, one of the sides being made removable, and cell-partitions formed of woven wire crimped into zigzag channels of half the thickness of an egg and two of said partitions forming one set of the egg-channels and having stay-braces at their ends to hold the eggs in the channels substantially as described.
